[57] CLAIM

The ornamental design for a bib for nursing mother, as shown and described.

DESCRIPTION

FIG. 1 is a front elevational view of a bib for nursing mother showing my new design;

FIG. 2 is a right side elevational view thereof, the left side being a mirror image;

FIG. 3 is a rear elevational view thereof;

FIG. 4 is a top plan view thereof;

FIG. 5 is a bottom plan view thereof;

FIG. 6 is a front elevational view thereof, the right panel being pulled aside as in the position of use; and

FIG. 7 is a front elevational view thereof, the left panel being pulled aside as in the position of use.

FIG. 1
